UNITED STATES PATENT OFFICE.

RUSSELL P. HARSHBERGER, OF CHICAGO, ILLINOIS.

SAFETY-RAZOR.

1,200,493.

Specification of Letters Patent. Patented Oct. 10, 1916.

Application filed September 14, 1915. Serial No. 50,553.

To all whom it may concern:

Be it known that I, RUSSELL P. HARSHBERGER, a citizen of the United States, residing at Chicago, in the county of Cook and 5 State of Illinois, have invented certain new and useful Improvements in Safety-Razors, of which the following is a specification.

This invention relates to improvements in safety razors and particularly to that class 10 of safety razors the blade of which is given a transverse motion during the cutting process.

One of the objects of the invention is to produce simple means for imparting transverse vibratory movement to the blade in a manner such as to allow the mechanism to be entirely inclosed in a casing, thereby excluding moisture and dirt from the mechanism, and also arranged so that the casing, together with the blade and guards, may be 20 quickly and conveniently removed and cleaned.

A further object of the invention is to produce a novel way of attaching the guard 25 and blade to the frame or handle of the razor so that they may be conveniently removed, and to provide various forms of guards so as to adapt the razor to the needs of particular persons or to certain portions of the face.

30 Of the accompanying drawings Figure 1 is an elevation of a safety razor embodying the features of my invention. Fig. 2 is a fragmental view at right angles to Fig. 1 partly in section. Fig. 3 is an enlarged sectional view of the operating mechanism. Fig. 4 is a section along the line 4—4 of Fig. 3. Fig. 5 is an end view of the frame of the razor. Fig. 6 is a plan view of the face guard of the razor. Fig. 7 is a plan view of the under side of the cap guard of the razor. Fig. 8 is a plan view of the cutting blade of the razor.

In general the razor comprises a cutting blade with suitable guards mounted on a 45 frame fixed to a handle, the blade being fixed to a vibrator casing which is loosely mounted in the frame, and which incloses an electric vibrator. The frame 11 has an opening 12 therethrough formed by side walls 13 and 50 14. A handle 15 is fixed, by means of threads 16, to the frame. A vibrator casing 17 is loosely mounted in the opening 12, so

that it is free to vibrate with reference to the frame, and may be easily slipped from the frame, through either end of the opening 12. Lugs 18 project outwardly from said casing 17, through an elongated slot 19 in the end plate 20 of the frame. The posts 18 are cylindrical in form, and the outer ends are adapted to pass through openings 21 in the razor blade 22. When the blade is in place on these posts it rests against shoulders 23, and is thus held spaced from the casing 17. In this manner the blade is 60 removably fixed to the casing, and vibrates therewith; but may be readily lifted outwardly from off the posts when the cap guard 30 is removed.

Guides 24 are fixed to the upper end of the frame 11, upon which is slidably mounted the face guard 25, so that the guard may be conveniently removed from the frame by sliding it along the guides. When the razor is assembled, the posts 18 pass through an elongated opening 26 in the guard, and the 70 blade, supported by said posts, is spaced external of the guard a slight distance therefrom. The opening 26 is of such size as to allow the posts to pass freely therethrough, so as to allow a sufficient amount of relative 75 vibration of the posts 18 and the guard 25.

Projecting outwardly from the guard 25 are posts 27 which pass loosely through the elongated openings 28 of the blade. The posts 27 pass into an elongated recess 29 in 85 the cap guard 30. The lengths of the posts 27 being such as to space the cap guard slightly away from the blade; and the openings 28 being of such size as to allow sufficient vibration between the blade and the 90 two guards. Spring clips 31 are fixed to the cap guard, and, when the razor is assembled, the clips pass over the ends of the face guard 25, as indicated in Fig. 2, holding the cap guard firmly in place. With this arrangement it will be seen that, when it is desired to clean the instrument, or change the blades, it is necessary only to pull cap guard 30 outwardly away from the face guard; pull the blade 22 outwardly from the 100 posts 18, and, if desired, the face guard 25 may be removed by removing the casing 17 in the manner hereinafter described.

In order to operate the vibrator, any suit-

able source of electric energy may be used. The electric current is conveyed to the vibrator, by means of the wires 35 and 36. These wires are insulated in a common manner, and, in this instance, pass through the opening 33 of the handle 15. The wire 36 is passed through another opening 34 in the handle, and is soldered, or fastened in any suitable manner, to the frame 11. Wire 35 5 is fastened, in any suitable manner, to a screw 38, which is threaded into an insulation member 39. The head of the screw 38 is cup shaped, and into the depression 40 projects a screw 41, making electric contact with the screw 38. The screw 41 is insulated from the casing by means of the insulation member 42; and the wire 43, which leads to the coils 44 of the electromagnet, is electrically connected to the screw 41 in any 10 suitable manner. The return wire 45, of the coils 44, is electrically connected to the spring 46 which is insulated from the casing by means of an insulation member 47. Spring 46 is fixed to the armature 47 of the 15 electromagnets, and the armature 47 is pivoted, in an insulation bracket 48 fixed to the casing 17. By this means the electric current passes into the armature 47 and through contacts 49 and 50 and spring 51 to the casing 17. As is well understood, when the 20 current passes into the coils of the electromagnet the armature will be drawn to the electromagnet, and the contacts 49 and 50 will be opened. The spring 46 will then 25 force the armature away from the electromagnet again closing the circuit, and the 30 operation will be repeated.

In order to cause sufficient vibration of the casing 17 I have provided the armature 47 with a weight 52. As the armature vibrates the weight is forced against the electromagnet, or against the wall of the casing, and thus causes the entire casing, together 40 with the attached blade, to vibrate. An insulation member 53 prevents the weight from coming in contact with the casing. By this means I am able to obtain a vibration of the blade, parallel with the cutting edge thereof, without any mechanical connection between the blade and the mechanism within the casing. I am thus able to have the mechanism entirely inclosed so as 45 to prevent the entrance of moisture or dirt, and so that the apparatus may be cleaned at 50 any time without danger of injury to the delicate portions of the mechanism.

When it is desired to clean the casing or remove the guard 25 it is necessary only to slip the casing out of the frame at either 55 end of the opening 12. As there is no positive mechanical connection between the casing and the frame the casing may be very easily removed or returned. If it is desired to open the casing the plate 54 may 60 be removed by first removing screw 55.

Although I have described with some particularity the various details of the structure which I have shown as an illustration of my invention, yet it is to be understood that modifications may be made therein by 70 those skilled in the art without departing from the spirit of my invention as disclosed by the following claims.

I claim as my invention—

1. Vibrating means comprising a frame 75 and a closed casing, a member to be vibrated rigidly fixed to said casing, and a vibrator inclosed within said casing, said casing being loosely mounted in said frame whereby said casing may be vibrated relative to said 80 frame.

2. Vibrating means comprising a frame, a casing loosely mounted in said frame, a member to be vibrated rigidly mounted on said casing, an electric vibrator fixed to 85 said casing, the armature of said vibrator being weighted, whereby said member is adapted to be vibrated relative to said frame.

3. In a safety razor, a frame, a casing 90 loosely mounted in said frame, a blade fixed to said casing, and a vibrator mounted in said casing and adapted to vibrate said blade and said frame relative to each other.

4. In a safety razor a frame, a guard 95 fixed to said frame, a casing loosely mounted in said frame, a blade fixed to said casing, and a vibrator mounted in said casing and adapted to vibrate said casing and blade with reference to said frame.

5. A safety razor comprising a frame, a guard fixed to said frame, a casing loosely mounted in said frame, said guard having an elongated aperture therethrough, lugs projecting from said casing through said 10 aperture, a blade fixed to said lugs, and a vibrator in said casing.

6. A safety razor comprising a frame, a guard having an elongated aperture therethrough fixed to said frame, a casing loosely mounted in said frame, a lug projecting from said casing and passing loosely through said aperture, a blade having openings therethrough, said lug passing snugly through one of said openings, a lug projecting outwardly from said guard through another opening through said blade, a cap guard having a recess therein, the lug of said guard passing into said recess, and means for holding said cap guard to said other guard.

7. A safety razor comprising a frame, a guard fixed to said frame, a casing loosely mounted in said frame, a blade fixed to said casing external to said guard, and spaced therefrom, a second guard fixed to said other guard external to said blade and spaced therefrom, and a vibrator in said casing.

8. A safety razor comprising a handle, a 1

blade, a face guard, and a cap guard; said blade being positioned between said guards; and means operatively connecting said blade with said handle; said blade having 5 apertures therethrough; posts projecting from said face guard through said apertures; said cap guard having an elongated recess therein to receive said posts; and clips fixed to said cap guard projecting over the ends of said face guard. 10

In testimony whereof, I hereunto set my hand.

RUSSELL P. HARSHBERGER.
